(57) **CLAIM**

The ornamental design for a "jewelry component," as shown and described.

DESCRIPTION

FIG. 1 is a perspective view of a jewelry component showing my new design;

FIG. 2 is a front view thereof;

FIG. 3 is a top view thereof;

FIG. 4 is a bottom view thereof; and,

FIG. 5 is a bottom perspective view thereof.

The rear view, the left side view and the right side view of the jewelry component are herein omitted, because they are the same as the front view of the jewelry component.
